METHOD OF DISTILLING BITUMINOUS COAL WITH RECOVERY OF GASEOUS DISTILLATE.

Application filed August 19, 1925. Serial No. 51,124.

This application is a continuation in part of our prior application Serial No. 21,469, filed April 8, 1925.

Our invention relates to methods of distilling bituminous coal for producing coke with recovery of the gaseous distillate.

The invention as will hereinafter more fully appear has among its objects the recovery of an economically valuable fraction of the gaseous distillate heretofore wasted by prior methods with the elimination of smoke and danger to the operators, and will be best understood from the following description when read in light of the accompanying drawings illustrating an example of apparatus for carrying out the improved method, while the scope of the invention will be more particularly pointed out in the appended claims.

20 In the drawings:—

Fig. 1 shows a transverse section of one form of apparatus for carrying out our method;

25 Fig. 2 is the front elevation according to Fig. 1;

Fig. 3 is a section showing a detail of the door closing that end of the oven adjacent the leveling machine; and

30 Fig. 4 is a plan of a fragment of the leveling bar.

We will first describe by reference to the drawings a preferred example of apparatus for use in carrying out our improved method, it being understood that we are not limited to this example.

35 In the drawings we have illustrated a battery of horizontal, elongated coke ovens 1, the ovens being arranged parallel to each other in closely adjacent relation as is illustrated in Fig. 2, and the battery in practice commonly consisting of from ten to one hundred ovens.

The ovens are heated by means of gaseous products of combustion passed through the flues 3 beneath the floors of the ovens and through the flues 5 in the walls separating the ovens as is common practice in apparatus of the kind described.

40 For charging the ovens we have shown for each a charging opening or hole 7 formed through the roof of the oven at a point intermediate its length, preferably midway the length of the oven. The charging opening 7, which preferably is substan-

tially of the same width as the oven, is 55 closed during the distilling and coking operations by a cover 8 illustrated in Fig. 1 as lying on the roof of the oven beside the charging opening. Coal is delivered through the openings 7 by gravity from the 60 chute 9 of the hopper 11 of a coal larry somewhat diagrammatically illustrated at 13. The larry conveniently is mounted for movement longitudinally of the battery on tracks 15 carried above the ovens so that 65 the chute 9 may be presented to the charging openings of the several ovens of the battery as desired.

For removing the coal in the oven from beneath the charging opening thus causing 70 coal to be drawn from the larry and for uniformly leveling the coal and distributing it in the oven a leveling machine is provided indicated diagrammatically in its entirety at 17, the leveling machine being mounted 75 on tracks 18 so that it can travel the length of the battery for operation on the several ovens. The leveling machine comprises a leveling bar 20 actuated by machinery (not shown) carried by the leveling machine, the 80 leveling bar when in operation reciprocating in a line passing beneath the charging opening. As illustrated the leveling bar comprises a pair of spaced side members 21 connected at spaced points by transverse members 22. As the leveling bar is reciprocated coal is entrained in the interstices between the transverse members 21 and thus moved through the oven. The operator controls the actuation of the leveling bar so that it 85 is reciprocated as desired with varying lengths of stroke and with varying amounts of extension into the oven so as to operate on the coal at different points in the oven, thus enabling the operator to remove the 90 coal from beneath the charging opening and uniformly distribute it throughout the 95 length of the oven.

In addition to the leveling bar the leveling machine conveniently is provided with 100 a pusher (not shown) for pushing the coke out of the ends 23 of the ovens at the completion of the coking operation. As the pushing apparatus and the leveling apparatus are well known in the art and as they 105 form no part of our invention they will not be further described.

For closing the ends of the ovens we have

illustrated vertically moving doors 24 which doors are closed during the charging and coking periods and are opened to permit the coke to be pushed out of the oven at the completion of the coking operation. For permitting entry into the oven of the leveling bar during the charging operation the door 24 adjacent the leveling machine is provided with an opening or "chuck hole" 25 (Fig. 3) of sufficient size conveniently to permit passage of the leveling bar, the opening being provided with a door or "chuck" 26 hinged to the door 24 at 27 for closing the opening 25 after the bar is withdrawn at the completion of the charging and leveling operations.

Adjacent the ends of the several ovens are openings 28, these openings respectively being in communication with separate gas off-take pipes 29 each controlled by a valve 30. As illustrated the offtake pipes 29 at the opposite ends of the several ovens respectively communicate with gas collecting battery offtake pipes or mains 31 and 32 running the length of the battery of ovens at each side thereof, said mains acting to place an offtake pipe for one oven in communication with offtake pipes for other ovens so that the mains are effective for conducting the gaseous distillate from a number of ovens to suitable apparatus for moving, treating, and disposing or storing the gaseous distillate. For moving the gaseous distillate through the pipes 31 and 32 we subject these pipes to suction, preferably employing for this purpose exhaust fans, steam ejectors, or equivalent devices commonly used in connection with apparatus of the kind described.

It will be understood that when fresh coal is charged to the oven it is rich in constituents for forming the gaseous distillate and that these constituents are distilled off in great volume at the beginning of the distilling operation, the volume of the distillate rapidly decreasing as the operation progresses. Further it will be understood that not only the volume of the distillate but also its richness decreases as the distilling operation progresses. Thus when coal is first charged to the oven a great volume of highly volatile and rich gas is distilled off and the volume and richness of the gas gradually decrease as the operation continues. In practice we have found that for a distilling and cooking operation of twenty hours' duration the relation of the volume of distillate generated during the first hour to the volume of distillate generated during the last hour is in the order of 45 to 2.

In carrying out our improved method the battery of ovens is operated continuously and preferably in such a manner that separate ovens are being "pushed" and recharged successively at regular intervals, that is to

say if for example the battery contains 50 ovens and the duration of the distilling and coking operation on each individual oven is 20 hours a different oven of the battery will be "pushed" and recharged approximately 70 every 24 minutes. It will be observed that with this method of operation the distilling and coking operations for the several ovens of the battery at any given time will have proceeded in a different degree toward completion, and consequently that the volume and richness of distillate given off by the several ovens of the battery at any given time will be different.

For economically utilizing the distillate 80 we have found in many instances that the rich gas and the lean should be separately collected, and to accomplish this result we connect all the ovens of the battery during the first part of the distilling and coking 85 operation with one of the mains, say the main 31, and all of the ovens of the battery during the final part of this operation to the other main 32, both mains being subjected to suction. For securing this particular result, when the distilling operation on a particular oven reaches the point where the lean gas is generated communication is established between that oven and the main 32 and communication is interrupted between that oven and the main 31 by respectively opening the valve 30 associated with the main 32 and closing the valve 30 associated with the main 31. If separate utilization of the rich and the lean 95 gases is desired the mains 31 and 32 will lead to separate places of disposal or storage of the gas conducted by them, in which case the gas collected by the main 31 may economically be used for domestic supply purposes 105 and the gas collected by the main 32 may be used for industrial supply purposes. If separate utilization of the rich and the lean gases is not desired the gases conducted by the mains 31 and 32 may be mixed by leading 110 the gases to a common place of disposal or storage, in which case both mains may communicate with the several ovens throughout the entire period of distillation, or one of these mains may be used to collect all the gas 115 except the excess generated during the charging operation as will hereinafter be more fully explained.

Not necessarily but ordinarily when rich and lean gases are separately collected it 120 will be found advantageous to subject the main 32 collecting lean gas or the excess of gas generated during the charging operation to a greater suction than the main 32. When separately collecting the rich and the 125 lean gases the degree of suction to which the mains 31 and 32 are subjected and the length of time an oven is connected to each of these mains are for a given coal to a large extent governed by the exact nature of the 130

distillate which is to be collected by the several mains as the degree of suction influences the constituents of the gas. As an example of the practice of our method but without limitation thereto we have found when separately collecting the rich and the lean gases that satisfactory results may be obtained by maintaining a suction of approximately 0.05 inches of water in the main 31 and a suction of about 0.20 inches of water in the main 32, an oven being connected to the main 31 for about 9 hours and to the main 32 for about 11 hours. It will be noted that by thus connecting the several ovens to the mains 31 and 32 the quality of gas collected by each main is the average of the quality of the gas generated by those ovens connected to each main, and as the ovens of the battery are charged and pushed at approximately regular intervals this average quality of the gas will be practically a constant.

It will be understood that the temperature of the oven gradually rises during the distilling and coking operation until it is a maximum at the completion of the coking operation when the oven is "pushed" to remove the coke and is recharged with fresh coal. Thus when charged to the oven the coal is subjected to higher temperatures than at any time thereafter until approximately the completion of the coking operation. This subjecting of the coal to high temperatures when charged causes an enormous initial distillation of gas which we estimate for the charging period is in the order of six to ten times the volume of the average distillation for the first hour's duration of the distilling operation. Furthermore as the richest and most volatile gases distill off first these initial distillates constitute a very high economic fraction of the total amount of distillate.

By prior methods the initial distillates generated during the charging operation are wasted, the gas being permitted to escape through the openings of the oven until the charging operation is completed. These escaping gases, which frequently ignite with resulting serious injuries to the operators, form dense clouds of smoke highly objectionable in residential districts and prohibited by the smoke nuisance laws of most, if not all, municipalities. By our improved method these initial distillates of high economic value are collected and the escape of gas and formation of smoke clouds are entirely eliminated, thus effecting a material increase in the recovery of distillate with safety to the operators and permitting our method to be carried out in plants situated in or adjacent to residential districts.

In order to describe an example of one way in which our improved method may be performed it will be assumed use is made of the apparatus hereinbefore described and

that the oven has been "pushed" to remove the coke and the oven is to be recharged. Under these conditions the doors 23 at the ends of the oven are closed and sealed with clay and the cover 8 is removed from the charging opening 7 in the roof of the oven. The larry is then moved to position over the oven with its chute presented to the charging opening and all the coal that will flow from the larry into the oven by gravity is permitted to do so, thus forming a pile of coal illustrated at 35 in Fig. 1 completely filling the charging opening and thus sealing the charging hole while isolating one end of the oven from the other. The operator, at the time coal commences to flow into the oven from the larry, opens both valves 30 thus permitting the exceedingly rich distillate, which as heretofore explained is then rapidly generated, to flow from the oven into both mains 31 and 32. When the pile of coal 35 is thus formed the "chuck" or door 26 is then moved on its hinge to open the "chuck hole" 25 and the leveling bar is entered and operated to remove coal from the top of the pile 35 and distribute it over the floor of the oven. As coal is removed from the pile 35 fresh coal is drawn or flows from the larry into the oven keeping the charging hole sealed, the leveling operation being continued until the oven is filled at each side of the charging hole to a level just below the roof sufficient to leave a space for permitting unobstructed flow of gas in the oven above the coal toward the distillate offtake openings 28. The empty larry is then moved from above the oven leaving a small pile of coal illustrated at 36 in Fig. 1 on the roof of the oven which in conjunction with the coal then filling the charging hole seals the charging opening. The leveling bar is then operated to remove sufficient coal from beneath the charging hole to cause the level of the coal on the roof of the oven to fall sufficiently to permit the cover 8 being placed in position to close the charging hole. After being placed in position the cover is sealed with clay and the leveling bar is operated to level the coal beneath the charging hole whereupon the leveling bar is withdrawn and the "chuck" 26 is closed and sealed with clay. The charging operation is now completed and if rich and lean gases are to be separably collected the valve 30 leading to the main 32 collecting the lean gas from other ovens is closed as soon as the volume of rich distillate decreases to a value which will permit the rich distillate collecting main 31 to carry it off. Usually such decrease in volume occurs with or shortly after the completion of the charging operation.

It will be observed that during the charging operation before communication is established between opposite ends of the oven

27 by the leveling of the coal the opposite ends
28 of the oven are effectively isolated from each
29 other by the coal under the charging opening.
30 Thus while the rich distillate at the
31 end of the oven adjacent the main 31 may
32 enter that main, the rich distillate at the op-
33 posite end of the oven is prevented from do-
34 ing so and is forced to enter the main 32.
35 On a battery of fifty ovens separately col-
36 lecting rich and lean gas operated accord-
37 ing to our improved method we have found
38 that the increased amount of rich distillate
39 recovered raises the heat value of the lean
40 gas delivered by the main 32 about 50 B. t. u.
41 per cubic foot as compared with the prior
42 method.

43 As heretofore explained, during the charg-
44 ing operation and immediately following it
45 the rich distillate may be generated at a
46 relatively large volume beyond the capacity
47 of the main 31 to remove all of it from the
48 oven as fast as it is generated if and when
49 all the gas has access to it, and it will be
50 observed that by opening the valve 30, as-
51 sociated with the main 32 we have effected
52 collection of rich distillate in excess of the
53 capacity of the main 31 and an increase in
54 the suction on the oven by increasing both
55 the effective offtake area and the effective
56 degree of suction, the latter following from
57 the fact that each main 31, 32 is subjected
58 to suction. The increased suction effective-
59 ly causes all the distillate generated during
60 the charging operation to flow into the mains
61 31 and 32 and prevent the escape of distil-
62 late through the chuck hole or other inci-
63 dental openings of the oven.

64 It will be observed that in the above
65 practice of our improved method the dis-
66 tillation process is initiated simultaneously
67 with the initiation of the charging operation
68 and that the oven is substantially sealed
69 throughout the charging operation. Fur-
70 thermore during the charging operation the
71 distillate generated in each end of the oven
72 is collected by effecting offtake of distillate
73 by suction at each side of the charging open-
74 ings of the ovens we cause a flow of gas
75 in opposite directions from the charging
76 openings, thus preventing escape of gas
77 through the charging openings if the flow
78 of coal from the larry is accidentally or
79 deliberately interrupted for any reason,
80 which escape of gas would occur due to the
81 low specific gravity of the gas if it were
82 caused to flow past the charging openings.

83 It will be understood that the degree of
84 suction to which the oven is subjected need
85 not be such as to cause a pressure below at-
86 mospheric, it being sufficient that the gas
87 pressure in the oven is lower than that pres-
88 sure which would cause the escape of gas
89 through the coal sealing the charging open-

90 ings or through other means of escape of
91 gas to the atmosphere.

92 The action which would result from at-
93 tempting to charge the ovens having but a
94 single distillate discharge opening or but
95 two distillate discharge openings and in
96 either case a plurality of charging openings,
97 can be appreciated by assuming the oven
98 arranged as indicated in dotted lines in Fig.
99 1 in which 37 are assumed charging points.
100 With this assumed arrangement when the
101 coal is charged piles of coal will be formed
102 at 39 which will trap gas between them and
103 this gas by its pressure will be forced through
104 the charging holes or other openings and
105 the interstices of the oven walls to the ex-
106 terior of the oven with resultant loss of dis-
107 tillate and formation of dense clouds of
108 smoke. If two distillate discharge openings
109 and three charging points were provided,
110 for example the above mentioned assumed
111 charging points 37 in addition to the single
112 charging point 7 illustrated in the submitted
113 example of apparatus for carrying out our
114 method, a particularly violent discharge of
115 distillate and smoke would be forced
116 through the opening 7.

117 Although our method may be practiced on
118 ovens provided with a plurality of charg-
119 ing openings we have found that a larry
120 with a single chute is lighter in weight than
121 one with a plurality of chutes and that it is
122 cheaper to manufacture, which results in
123 lower installation costs, yet it can be used to
124 charge the same oven with greater ease of
125 operation and a saving of labor costs. We
126 have found, for example, that the provision
127 of a single charging opening insures effect-
128 ing complete sealing of the oven by the coal
129 during the charging and leveling opera-
130 tions, whereas if more than one charging
131 opening is employed it is impossible to pre-
132 vent the coal being drawn entirely out of
133 one or more charging openings in attempt-
134 ing to spread the coal below other charg-
135 ing openings, which will be obvious from
136 a consideration of Fig. 1 of the drawings
137 if it is assumed the leveling bar is operating
138 on the pile of coal under the left hand
139 charging opening 37, which will draw coal
140 not only away from the left hand charging
141 opening but also away from the other two
142 charging openings with the result that the
143 coal will be drawn entirely from one or
144 both of the latter openings if the larry be-
145 comes empty during this operation, it being
146 understood that in order to draw sufficient
147 coal into the oven by use of the leveling bar
148 the left hand pile of coal must be operated
149 upon after all the coal that initially will fall
150 into the oven through the left hand charg-
151 ing opening has entered the oven. It will be
152 observed that the more charging openings
153 employed the greater the proportion of the
154 charge that initially falls into the oven and

the less the reserve of the total charge remaining in the larry. When a charging opening is unsealed air will enter the oven and by partial combustion produce amounts of smoke with increases in the pressure above those which ordinarily would occur.

It will be understood that our improved method relates to the recovery of gas whether this or the recovery of coke is the primary commercial object of the practice of the method.

It will be understood that we are not limited to the examples of apparatus and practice of the method herein described, but that within the scope of the invention wide deviations may be made therefrom without departing from its spirit.

Claims:

1. That method of operating a battery of coke ovens having charging openings in the roofs thereof and distilling bituminous coal with collection for use of the gaseous products by suction during substantially the entire operation, which comprises charging the ovens while hot through the charging openings, and eliminating smoke by effecting offtake of gaseous products at opposite sides of the charging openings of the ovens during the charging operations thereon while subjecting the ovens to increased suction during the charging operations.

2. That method of operating a battery of coke ovens having charging openings in the roofs thereof and distilling bituminous coal with collection for use of the gaseous products by suction during substantially the entire operation, which comprises charging the ovens while hot through the charging openings, and eliminating smoke by effecting sealing of the charging openings by the coal being delivered to the ovens during the charging operations, effecting offtake of gaseous products at opposite sides of the charging openings of the ovens during the charging operations thereon while subjecting the ovens to increased suction during the charging operations.

3. That method of operating a battery of exteriorly heated coke ovens each having a substantially single charging opening in the roof thereof with collection for use of gaseous products by suction during substantially the entire operation, which comprises delivering bituminous coal to the ovens while hot through the charging openings, collecting for use the rich gaseous products rapidly generated during the charging operations by effecting offtake of gaseous products by suction at opposite sides of the charging openings, the effective aggregate offtake area for each oven during the charging operation thereon being materially in excess of that for effecting collection of gaseous products from the other ovens of the battery already charged and generating a normal volume of

distillate, while placing the offtakes for the gaseous products during the charging operations in communication with the offtakes for the gaseous products being collected from other ovens of the battery.

4. That method of operating a battery of exteriorly heated coke ovens having charging openings in the roofs thereof with recovery for use of gaseous products by suction during substantially the entire operation, which comprises delivering bituminous coal to the ovens while hot through the charging openings, collecting the rich gaseous products rapidly generated during the charging operations by effecting offtake of gaseous products by suction at opposite sides of the charging openings, the effective degree of suction on each oven during the charging operation thereon being materially in excess of the degree of suction for effecting a collection of gaseous products from the other ovens of the battery already charged and generating a normal volume of distillate, while placing the offtakes for the gaseous products during the charging operations in communication with the offtakes for the gaseous products being collected from other ovens of the battery.

5. That method of operating a battery of exteriorly heated coke ovens having charging openings in the roofs thereof with recovery for use of gaseous products by suction during substantially the entire operation, which comprises delivering bituminous coal to the ovens while hot through the charging openings, collecting the rich gaseous products rapidly generated during the charging operations by effecting offtake of gaseous products by suction at opposite sides of the charging openings, the effective aggregate offtake area and the effective degree of suction for each oven during the charging operation thereon being materially in excess of the offtake area and degree of suction for effecting collection of gaseous products from the other ovens of the battery already charged and generating a normal volume of distillate, while placing the offtakes for the gaseous products during the charging operations in communication with the offtakes for the gaseous products being collected from other ovens of the battery.

6. That method of operating a battery of exteriorly heated coke ovens each having a substantially single charging opening in the roof thereof with recovery for use of gaseous products by suction during substantially the entire operation, which comprises delivering bituminous coal to the ovens while hot through the charging openings, effecting sealing of the charging openings during the charging operations, collecting the rich gaseous products rapidly generated during the charging operations by effecting offtake of gaseous products by suction at opposite

sides of the charging openings, the effective aggregate offtake area for each oven during the charging operation thereon being materially in excess of that for effecting collection of gaseous products from the other ovens of the battery already charged and generating a normal volume of gaseous products.

7. That method of operating a battery of exteriorly heated coke ovens each having a substantially single charging opening in the roof thereof with recovery for use of gaseous products by suction during substantially the entire operation, which comprises delivering bituminous coal to the ovens while hot through the charging openings, effecting sealing of the charging openings during the charging operations, collecting the rich gaseous products rapidly generated during the charging operations by effecting offtake of gaseous products by suction at opposite sides of the charging openings, the effective degree of suction on each oven during the charging operation thereon being materially in excess of the degree of suction for effecting collection of gaseous products from the other ovens of the battery already charged and generating a normal volume of gaseous products.

8. That method of operating a battery of exteriorly heated coke ovens each having a substantially single charging opening in the roof thereof with recovery for use of gaseous products by suction during substantially the entire operation, which comprises delivering bituminous coal to the ovens while hot through the charging openings, effecting sealing of the charging openings during the charging operations, collecting the rich gaseous products rapidly generated during the charging operations by effecting offtake of gaseous products by suction at opposite sides of the charging openings, the effective aggregate offtake area and the effective degree of suction for each oven during the charging operation thereon being materially in excess of the offtake area and the degree of suction for effecting collection of gaseous products from the other ovens of the battery already charged and generating a normal volume of gaseous products.

9. That method of operating a battery of exteriorly heated coke ovens with collection for use of gaseous products by suction during substantially the entire operation, which comprises delivering bituminous coal by gravity to each oven while hot through a substantially single charging opening in the roof of the oven, leveling the coal after passing through the charging openings while uninterruptedly effecting delivery of coal to the charging openings in amounts substantially equal to those removed from beneath the charging openings by the leveling operations whereby during the charging

operations the charging openings are sealed by the coal, and effecting a continuous collection of the gaseous products during the charging and leveling operations at points at opposite sides of the charging openings through offtakes subjected to suction.

10. That method of operating a battery of exteriorly heated coke ovens with recovery of gaseous products by suction during substantially the entire operation, which comprises delivering bituminous coal by gravity to the ovens while hot through charging openings in the roofs of the ovens, leveling the coal after passing through the charging openings while uninterruptedly effecting delivery of coal to the charging openings in amounts substantially equal to those removed from beneath the charging openings by the leveling operations whereby during the charging operations the charging openings are sealed by the coal, collecting the rich gaseous products rapidly generated during the charging operations by effecting offtake of gaseous products at opposite sides of the charging openings by suction, and after completion of the charging operations on each oven effecting a decrease in the effective suction thereon.

11. That method of operating a battery of exteriorly heated coke ovens with recovery for use of gaseous products by suction during substantially the entire operation, which comprises delivering bituminous coal by gravity to each oven while hot through a substantially single charging opening in the roof of the oven, leveling the coal after passing through the charging openings while uninterruptedly effecting delivery of coal to the charging openings in amounts substantially equal to those removed from beneath the charging openings by the leveling operations whereby during the charging and leveling operations the charging openings are sealed by the coal, effecting a continuous collection of the gaseous products during the charging operations, until the coal is leveled, at points at opposite sides of the charging openings through different offtakes subjected to suction, and after completion of the leveling of the coal effecting closure of the offtakes at one side of the charging openings.

12. That method of operating a battery of exteriorly heated coke ovens with recovery for use of gaseous products by suction during substantially the entire operation, which comprises delivering bituminous coal by gravity to each oven while hot through a substantially single charging opening in the roof of the oven, leveling the coal after passing through the charging openings while uninterruptedly effecting delivery of coal to the charging openings in amounts substantially equal to those removed from beneath the charging openings by the leveling op-

- erations whereby during the charging operations the charging openings are sealed by the coal, effecting a continuous collection of the gaseous products during the charging operations, until the coal is leveled, at points at opposite sides of the charging openings through offtakes to different battery mains for rich and lean gas respectively subjected to different degrees of suction, the degree of suction for the main for lean gas being greater than that for the main for rich gas, and after completion of the leveling of the coal effecting closure of the offtakes to the main for lean gas and thereafter effecting closure of the offtakes to the main for rich gas while effecting opening of the offtakes to the main for lean gas.
13. That method of operating a battery of horizontal coke ovens with collection for use of gaseous products, which comprises charging each oven through the roof thereof by gravity at a substantially single charging point intermediate the length of the oven, leveling the coal while uninterruptedly delivering the coal in amounts substantially equal to those removed from beneath the charging point by the leveling operation, and effecting offtake of gas by suction at points adjacent opposite ends of the oven during substantially the entire distilling period beginning with the initiation of the charging operation.
14. That method of distilling bituminous coal with recovery for use of gaseous products utilizing a battery of exteriorly heated coke ovens, which comprises pushing and charging the ovens of the battery consecutively, effecting a separate collection for use by battery gas offtake mains of the rich and lean gas from the battery respectively generated in individual ovens during different portions of the period following charging and leveling the coal therein while subjecting the battery offtake mains to suction, charging the coal to the ovens while hot through charging openings in the roofs of the ovens, and effecting a discharge of the gas generated during the charging operation for each oven into both the rich and lean gas offtake mains of the battery.
15. That method of distilling bituminous coal with recovery for use of gaseous products utilizing a battery of exteriorly heated coke ovens each having a substantially single charging opening in the roof thereof, which comprises pushing and charging the ovens of the battery consecutively, effecting a separate collection by battery gas offtake mains of the rich and lean gas from the battery respectively generated in individual ovens during different portions of the period following charging and leveling the coal therein while subjecting the battery offtake mains to suction, charging the coal to the ovens while hot through the charging openings,
16. That method of distilling bituminous coal with recovery for use of gaseous products, utilizing a battery of exteriorly heated coke ovens each having a substantially single charging opening in the roof thereof, which comprises pushing and charging the ovens of the battery consecutively, effecting a collection through openings communicating with a battery gas offtake main of gas generated by individual ovens beginning with the initiation of the charging operations, charging the coal to the ovens while hot, effecting sealing of the ovens while the coal is being charged thereto and leveled, and collecting the gas generated during the charging and leveling operations in excess of the capacity of the main to remove it from the ovens by effecting separate offtake of such excess through openings independently subjected to suction.
17. That method of distilling bituminous coal with recovery for use of gaseous products, utilizing a battery of exteriorly heated coke ovens each having a substantially single charging opening in the roof thereof, which comprises consecutively pushing and charging the ovens, effecting by battery gas offtake mains subjected to suction a continuous collection of gas at points at opposite sides of the charging openings of the battery of ovens generated by individual ovens beginning with the initiations of the charging operations, charging the coal to the ovens while hot, and effecting sealing of the ovens by the coal while the coal is being charged thereto and leveled.
18. That method of distilling bituminous coal with recovery for use of gaseous distillate, utilizing a battery of exteriorly heated coke ovens, which comprises pushing and charging the ovens of the battery consecutively, effecting a collection by a battery gas offtake main subjected to suction of gas from the battery of ovens generated by individual ovens beginning with the initiation of the charging operation, charging the coal to the ovens while hot, effecting sealing of the ovens while the coal is being charged thereto and leveled, and collecting the gas generated during the charging and leveling operation in excess of the gas collecting capacity of the main to remove it from the oven by effecting during the charging and leveling operations on each oven offtake of such excess by increasing the suction on the oven to a value above that to which it is subjected by said main.
19. That method of distilling bituminous coal with recovery for use of gaseous prod-

- ucts utilizing a battery of exteriorly heated coke ovens, which comprises pushing and charging the ovens of the battery consecutively, separately collecting the rich and lean gas generated by the ovens of the battery respectively through different offtake openings in the ovens subjected to suction, effecting a greater suction on the openings collecting lean gas than on those collecting rich gas, charging the ovens while hot through charging openings in the roofs thereof and situated intermediate the offtake openings for collecting rich and lean gas, leveling the coal after passage through the charging openings while delivering coal to the charging openings uninterruptedly in amounts substantially equal to those removed from beneath the charging openings during the leveling operations whereby during the charging and leveling operations the charging openings are sealed by the coal, and collecting the rich gas generated during the charging and leveling operations through said offtake openings while maintaining the suction thereon.
20. That method of operating a battery of exteriorly heated, elongated, horizontal coke ovens with collection for use of gaseous products during substantially the entire operation, which comprises delivering bituminous coal to each oven while hot through a substantially single charging opening in the roof of the oven at a point intermediate its ends, leveling the coal while uninterruptedly delivering the charge to the charging opening in amounts substantially equal to those removed from beneath the opening by the leveling operation whereby during the charging and leveling operations the charging opening is sealed by the coal, effecting continuous offtake of gaseous products by suction from the ovens at opposite sides of the charging openings beginning with the initiations of the charging operations, and charging and pushing the ovens of the battery consecutively.
21. That method of operating a battery of exteriorly heated, elongated, horizontal coke ovens, which comprises sealing the ovens during the charging and leveling operations by delivering the charge of coal to each oven through a substantially single charging opening in the roof of the oven at a point intermediate its ends, leveling the coal while uninterruptedly delivering the charge to said charging opening in amounts substantially equal to those removed from beneath the charging opening by the leveling operation, and effecting during the charging and leveling operations and thereafter offtake of gaseous products from opposite sides of the charging openings by suction at points above the coal.
22. That method of operating a battery of exteriorly heated, elongated, horizontal coke ovens for distilling bituminous coal and having charging openings in the roofs thereof intermediate their ends, which comprises charging the ovens while hot, and removing, during the charging operations, the gaseous products generated from the coal delivered through said openings to the ovens, while preventing escape of said products from the ovens through said openings, by delivering the coal to said openings by gravity, leveling the coal in the ovens as the coal gravitates thereinto through said openings, while supplying the coal to said openings in amounts sufficient to keep them sealed by the coal during the charging operations, and simultaneously withdrawing said gaseous products by suction at points at opposite sides of said openings.

In testimony whereof, we have signed our names to this specification.

ROBERT M. FOLSOM.
CHARLES A. RAYMOND.
